FRANK A. YOUNG, OF MERIDEN, CONNECTICUT, ASSIGNOR, BY MESNE ASSIGNMENTS, TO RADIO INVENTIONS, INC., OF NEW YORK, N. Y., A CORPORATION OF NEW YORK

RECTIFIER

Application filed April 7, 1926. Serial No. 100,266.

My invention relates particularly to what are commonly termed cold cathode devices depending upon difference in area of the anode and cathode.

5 The main object is to provide a simple, durable and reliable device which can be commercially made.

Another object is to provide a device which will operate uniformly and economically.

10 Another object is to provide an efficient and durable device for full wave rectification.

In the preferred form, the device has two 15 anodes and a single cathode, all insulated from each other but mechanically inter-connected so as to reinforce each other.

Fig. 1 is an end view of the device with the tube being shown in cross-section.

20 Fig. 2 is a longitudinal sectional view and side elevation.

Fig. 3 is a perspective view showing the various internal parts.

The envelope or container 5 may be of any 25 suitable material, such as glass of any suitable shape.

The circuit terminals or conductors 6, 7, and 8 are brought out through a pressed stem or press 9. The cathode elements 10 is 30 preferably supported at opposite sides by the conductor 6 and a supplemental supporting rod 11 which is mounted in the press 9.

The anodes 12 and 13 are comparatively 35 small in area and located with respect to the cathode surfaces so as to permit a predominating one-way ionization. The anodes are spaced apart at all points of the cathode surfaces, a sufficient distance to permit ionization to take place. The anodes are 40 preferably of graphite, supported in sockets 14 which are mounted on the ends of pins 15, which, in turn, are connected to the terminal by a sealing-in wire 16. For convenience in manufacture, the lower end of the anode 45 may be nickel plated at 17 and then welded or soldered in the upper end of the tube 14. The lower end of the tube 14 is soldered or welded to the upper end of the pin 15. The tube 18 is of glass and surrounds the tubular 50 portion 14 of the anode base and itself is

sealed into contact with the upper end of the press 9. Around the upper end of the glass tubes 18 and the anode base, I mount an insulator 19 for preventing the transference of heat back to the press.

55 The two anodes and the cathode are braced with respect to each other and with respect to the press 9 by a reinforcing plate 20. This plate has lugs 21 which are welded to the supports 6 and 11. Additional bracing members 22 may be welded to the cathode 10 and the plate 20. The plate 20 is also preferably provided with raised bosses 23 which provide recesses beneath to receive the upper ends of the insulators 19. In this way the insulators are braced with respect to the plate 20 and the plate 20 is held by the posts 6 and 11, thus affording a four-point support for the plate 20. The plate 20 is provided with 60 passages 24 for the anodes. The insulators 65 are preferably provided with flanges 25 so as to leave a space beneath the boss 23 for the collection of material adjacent the edge of the opening 24 which might otherwise short-circuit the device.

70 The parts are made as light as practical not only to conserve material and save expense but also to prolong the life of the parts which are likely to be broken by impact and inertia if they are made too heavy. It is also 75 desirable to separate the parts as much as possible to bring a maximum cooling effect by radiation as well as convection.

Although I do not wish to be limited to the particular materials specified, I might 85 state that I have found good results can be attained by the use of nickel for the cathode 10, steel for the plate 20, lava for the insulator 19, graphite for the anodes, nickel for the tube 14 and pin 15, and glass for the insulating tube 18. After the parts have 90 been assembled, the tube is evacuated and an atmosphere of an inert gas, such as neon, is preferably provided. The pressure of this 95 gas may be equal to one and one-half centimeters of mercury. It should be understood, however, that I do not consider the invention as limited to this pressure or to that particular gas.

I claim:

1. A rectifier comprising an envelope having a press, a wire sealed in said press, a metallic tube secured on said wire, an insulator on said tube, and a graphite anode with a plated base secured in said tube and a cathode adjacent to said anode.
- 5 2. A rectifier comprising an envelope containing a wire, a metallic tube secured on said wire, lava and glass insulators on said tube, and a graphite anode with a plated base secured in said tube and a cathode adjacent to the anode.
